ATTORNEY

UNITED STATES PATENT OFFICE.

FRANK B. KEARNEY, OF GRAND RAPIDS, MICHIGAN, ASSIGNOR OF ONE-HALF
TO DAVID E. SPENCER AND GERSHOM POWERS, OF SAME PLACE.

TONGUING AND GROOVING MACHINE.

SPECIFICATION forming part of Letters Patent No. 313,000, dated February 24, 1885.

Application filed May 24, 1884. (No model.)

To all whom it may concern:

Be it known that I, FRANK B. KEARNEY, of the city of Grand Rapids, county of Kent, and State of Michigan, have invented a new and useful Improvement in Grooving and Tonguing Machines, of which the following is a specification, reference being had to the accompanying drawings.

My invention relates to the construction of a machine designed to seize, secure, and hold pieces of wood which are to be tongued and grooved for the purpose of joining them together, like flooring and matched table-tops, and when so secured and held to guide them firmly and evenly along a saw-table, to be subjected to the action of the saws, which project slightly above the top of the saw-table, the tonguing and grooving being done by the action of said saws, constructed, set, and adapted to the purpose.

Referring to the drawings, Figure 1 is a plan view of my invention. Fig. 2 is an end view of the same opened, and showing the saw-table in section. Fig. 3 is also an end view closed, without the table.

Similar letters of reference refer to corresponding parts throughout the several figures.

A A' represent two compression-rods, to which the springs e e e e are attached. B B' represent curved connecting-rods joining rods A A' with wheel D, Figs. 2 and 3. (These rods are represented by B B' upon the right of Fig. 1, and by L L' upon the left of same figure.)

C is a lever that turns shaft D.

D represents a central longitudinal shaft. (Shown in Fig. 1 by dotted lines, the end only being shown in Figs. 2 and 3.)

E is a dovetailed track which rests upon saw-table top, and engages with the longitudinal groove in the bottom of main guide-block M, Figs. 2 and 3. (This track may be double, if desired, and when double only one need be dovetailed.)

F indicates feed-screw. (This screw may be dispensed with and the device guided by hand, if desired.)

G indicates saw-table; N N', saws in posi-

tion; K, saw-shaft, and H H' wheels or disks rigidly secured to the ends of shaft D.

50

I I' and J J indicate guide-rods rigidly secured to main guide-block M and passing through A A' loosely; M, the main guide-block resting upon track E, and to which boards d d are rigidly pressed by springs e e e e; a a, 55 nuts fastening the connecting-rods to the compression-rods; c c c c, grooved portion of springs e e e e, by which they are detachably secured to rods A A' by set-screws, as shown in Fig. 1; d d, pieces of board in position to 60 be grooved; e e e e, springs.

The method of operating my device is as follows: Being placed upon the track E, (which has been firmly secured upon the top of the saw-table and laid perfectly straight and level,) 65 the grooved bottom engaging with the dovetailed top of track E, the lever C being laid horizontally, as shown in Fig. 2, rods B B' L L' will push rods A A' outward from block M. When the parts are in this position, I say the 70 machine is "open." The boards d d to be grooved are then placed in position, as shown in Fig. 1. The lever C is then raised perpendicularly, as shown in Fig. 2. The revolution of the shaft D, carrying the wheels H H', causes 75 the rods B B' L L' to draw in upon the rods A A', carrying the springs e e e e, which press against boards d d, pressing them firmly against main guide-block M, and holding them firmly, rigidly, and securely in that position. The device is then pushed forward along the track (either by hand or screw power, as hereinbefore stated, or other suitable means) until it has 80 passed over the saws, by the action of which the lower edges of d d will be tongued and grooved, 85 as shown in Fig. 2. The position of the pieces d d being then transposed, their other edges may be similarly treated by the backward movement of the machine.

Having thus described my invention, what I 90 claim as new, and desire to secure by Letters Patent, is—

1. The combination, with the main guide-block forming a support for the boards to be tongued and grooved, of the longitudinal shaft 95 passing through said block, the wheels at-

tached to the ends of said shaft, the connect-
ing-rods, and the compression-rods provided
with springs adapted to bear against the boards
and press them against the sides of the main
5 guide-block, substantially as specified.

2. The combination, with the main guide-
block, of the shaft passing longitudinally
through the same, the wheels attached to the
ends of the shaft, the operating-lever secured
10 to one of the wheels, the curved connecting-
rods pivoted to said wheels, the compression-
rods and their guide-rods, and the clamping-
springs, all arranged to operate substantially
as specified.

15 3. The combination of the main guide-block,
against which the boards are clamped, the
shaft extending longitudinally through said

block, the wheels secured to the ends of said
shaft, the curved rods connecting the com-
pression-rods with said wheels, the springs 20
secured to said compression-rods and adapted
to bear against the boards, and the dovetailed
track on which the main block travels, the
whole arranged to operate substantially as
specified.

25 In testimony that I claim the foregoing I
have hereunto set my hand, in the presence of
two witnesses, this 17th day of May, A. D.
1884.

FRANK B. KEARNEY.

Witnesses:

DENNIS L. ROGERS,
FRANK S. DONALDSON.
